TREATMENT OF HYDROCARBON OIL

Filed April 19, 1933

UNITED STATES PATENT OFFICE

2,121,209

TREATMENT OF HYDROCARBON OIL

William F. Moore, Bayside, N. Y., assignor to
Gasoline Products Company, Inc., Newark,
N. J., a corporation of Delaware

Application April 19, 1933, Serial No. 666,801

5 Claims. (Cl. 196—49)

This invention relates to the treatment of hydrocarbon oil, such as petroleum and oils derived from petroleum, for the recovery therefrom of valuable low-boiling oils such as gasoline or motor fuel. My invention has for an object the provision of a process adapted to obtain a maximum conversion of a petroleum oil into valuable products more especially low-boiling products such as gasoline or motor fuel, and to produce reduced amounts of relatively less valuable products such as gas and fuel oil or tar.

My invention has for further objects such additional improvements in operative advantages and results as may hereinafter be found to obtain.

My invention contemplates a combined process wherein a petroleum oil, for example, a crude petroleum, may be distilled, with the selective treatment of various products of the distillation, including pyrolysis or cracking of a suitable stock or stocks resulting from the distillation step, and further selective treatment and combination, under conditions favorable for inter-reaction and the formation of valuable products, of products produced in the distilling and cracking operations, as well as materials such as gas or oil which may be drawn from outside sources.

More specifically, in one of its aspects my invention contemplates the reforming of gasoline or naphtha of relatively low anti-knock value to produce a gasoline or naphtha product of improved anti-knock value and the combining of the resultant products with relatively heavy petroleum oil, preferably a residual oil, and preferably a hydrocarbon oil containing reactive constituents, such, for example, as unsaturated hydrocarbons, in the presence of gaseous unsaturated hydrocarbons such as olefins, resulting from the reformation of the naphtha or gasoline or derived from an external source, under conditions effective to promote polymerization of normally gaseous constituents to normally liquid constituents. The conditions under which the combination is effected are so controlled as to cause inter-reaction to take place between the gaseous products of the reforming operation, as well as, when they are present, gaseous unsaturated hydrocarbons from outside sources, and relatively heavy liquid constituents also present, thereby resulting in the formation of more or less intermediate products such as motor fuel, naphtha or gasoline or oil suitable for cracking to produce motor fuel or gasoline having an improved anti-knock value.

Thus, I may subject a crude petroleum to

distillation under substantially non-cracking conditions, the products being separated and fractionated to recover a residual product or reduced crude, gas oil, virgin gasoline and gas, as well as such addition fractions, for example, lubricating oil stocks, as may be produced according to the nature of the original crude petroleum. According to one method of operation of my invention the virgin gas oil may then be cracked for the purpose of recovering a cracked gasoline fraction, gases, recycle gas oil, and residual oil or pressure tar. The gas oil thus produced may be recycled in the cracking unit. The virgin gasoline from the initial distillation step may then be subjected to heat treatment to effect a reformation of constituents thereof to constituents of improved anti-knock value, while the reduced crude resulting from the initial distillation operation may be subjected to a mild cracking temperature which may promote the formation of unsaturated or other reaction constituents, and the hot reformed products together with the products from the cracking of the reduced crude may be discharged into a common reaction zone which may also receive gases drawn from the distillation or cracking stages or from outside sources, either with or without pyrolysis at high temperature to promote the formation of unsaturated hydrocarbon constituents.

The various products delivered to the common reaction zone are digested together under conditions favorable for inter-reaction between gaseous and liquid unsaturated hydrocarbons or other reactive constituents, and preferably within a range of temperature and pressure effective to promote the polymerization of normally gaseous constituents to normally liquid constituents. The resultant vapors may then be withdrawn and fractionated to recover normally liquid and normally gaseous products therefrom, more particularly to effect the recovery of the gasoline or naphtha fraction.

As an alternative mode of procedure, I may subject the reduced crude or residual oil resulting from the initial distillation step, together with virgin gas oil, if so desired, to a cracking operation of more or less conventional character for the purpose of producing a cracked gasoline distillate, and the various products resulting from the cracking operation, such, for example, as gas and residual oil or pressure tar may be combined in a common reaction zone, either with or without preliminary treatment under selected conditions to promote the formation of reactive constituents such as unsaturated hydrocarbons.

- In any case, I may conduct a cracking operation in such manner as to recover, in addition to a light cracked gasoline distillate, a heavy gasoline or naphtha fraction suitable for reforming, and I may subject this heavy gasoline fraction to a reforming operation for the purpose of increasing its anti-knock value and its content of unsaturated hydrocarbons, the resultant reformed products being delivered to a reaction vessel which is supplied with a relatively heavy petroleum oil of the character indicated hereinabove. The resultant vapors are withdrawn and fractionated for the recovery of normally liquid constituents therefrom.
- I may also supply the gases liberated in the distilling stage, preferably supplemented by gases drawn from the cracking stage or from an outside source, to the aforesaid reaction stage, and where such gases contain relatively small amounts of unsaturated constituents, they may be subjected to an initial pyrolysis for the purpose of producing or increasing the amount of unsaturated hydrocarbons such as gaseous olefins.
- In order that my invention may be clearly set forth and understood, I now describe, with reference to the drawing accompanying and forming part of this specification, various preferred forms and manners in which my invention may be practiced and embodied, but without limiting my invention to such exemplifications. In this drawing:
- The single figure is a more or less diagrammatic view of a system for treating hydrocarbon oil in accordance with my invention.
- Referring to the drawing, a petroleum oil, such, for example as a crude petroleum of Mid-continent origin, is drawn from a source (not shown) through a conduit 1, wherein is located a pump 2, by means of which the oil may be passed to a heat-exchange coil 3 located within a fractionating tower 4, before passing through a conduit 5 to heating coils 6 and 7 located within a furnace 8.
- While in transit through the coils 6 and 7, the oil is heated to a sufficient temperature to effect the desired distillation, such for example, as from 600° to 750° F., and the heating of the oil may with advantage be conducted without any material cracking. The heated oil then flows through a line 9 having a pressure-reducing valve 10 to a separating compartment 11 located in the bottom of the fractionating tower 4. The separating compartment 11 may be provided with suitable baffles 12, as well as a reflux supply line 13, for the purpose of preventing entrainment of heavy or residual constituents of the oil being distilled. The vapors liberated in the separating compartment 11 pass upward through a trap-out tray 14 into the upper portion of the fractionating tower 4, which is provided with suitable plates or trays 15, and under the influence of the heat-exchange coil 3, a dephlegmating and fractionating action takes place, resulting in the condensation of a gas oil fraction which collects at the trap-out tray 14 and is withdrawn from the fractionating tower 4 through a conduit 16 having a valve 17 and a pump 18.
- The gases and vapors reaching the top of the fractionating tower 4 pass through a vapor line 21, a condenser 22 and a condensate line 23 to a gas separator 24, where a separation of condensate and uncondensable gas is effected. The gases are withdrawn through a conduit 25 having a valve 26 while the condensate, consisting

of virgin gasoline, is withdrawn through a conduit 27 having a valve 28.

A portion of the gas oil withdrawn from the trap-out tray 14 may be employed as a reflux either in the tower 4 or elsewhere. Thus, a portion of this gas oil may be withdrawn through a branch conduit 31 having a valve 32 and communicating with the conduit 16, to pass through a cooler 33 and a conduit 34 having a valve 35, to the reflux line 13, by means of which this oil may be reintroduced into the separating chamber 11.

The virgin gas oil not employed as a reflux may be delivered by the pump 18 through a conduit 36 having a valve 37, while the residual oil or reduced crude which separates in the bottom of the separating compartment 11 may be withdrawn therefrom from a conduit 38 wherein is located a pump 39.

In the drawing, I have illustrated a cracking plant comprising principally a furnace 41, a still 42 and a fractionating tower 43, which plant may be employed for cracking either virgin gas oil or reduced crude, or both. Thus, the virgin gas oil may be delivered by the pump 18 through conduits 16, 36, 44 and 45 to heating coils 46, 47 and 48 located within the furnace 41, wherein the gas oil is heated to any suitable cracking temperature such, for example, as from 850° to 1050° F. under such superatmospheric pressure as may be desired. When using a very clean stock the cracking may be carried on in the vapor phase. The resultant hot cracked products are then discharged through a transfer line 51 to the still 42, which may receive reduced crude from the pump 39 and conduit 38 through a branch conduit 52 having a valve 53 and leading to an intermediate portion of the still 42. The still 42 may be provided, as shown, with baffles 54 and may also receive cool reflux oil, preferably at a point above the point of admission of the reduced crude thereto. For example, such reflux oil may be supplied from the pump 18 and the cooler 33 through a conduit 55 having a valve 56.

Within the still 42, separation of vapors and residual oil takes place, the vapors passing through a vapor line 57 to the fractionating tower 43, while the residual liquid is withdrawn from the bottom of the still 42 through a conduit 58 wherein is located a pump 59 and a valve 60. In some instances, as for example when reduced crude is not charged to the still 42, it may be desirable to withdraw the residual oil or pressure tar from the bottom of the still 42 to remove it from the system. In other instances, such residual oil may be withdrawn through a branch conduit 62 having a valve 63.

Within the fractionating tower 43, which is preferably provided with plates or trays 64 and a cooling coil 65, the vapors withdrawn from the still 42 are subjected to a fractional condensation, which is carried out in such manner as to effect the condensation and accumulation at the bottom of the fractionating tower 43 of a gas-oil fraction which is preferably withdrawn from the tower 43 through a conduit 66 having a valve 67 and a pump 68. This gas oil may be recycled through the coils 46, 47 and 48 located within the furnace 41. Gases and vapors reaching the top of the fractionating tower 43 are withdrawn through a vapor line 71 to a condenser 72 from which the condensed products pass through a conduit 73 to a gas separator 74. The condensate, consisting of light cracked dis-

tillate or gasoline, is withdrawn from the separator 74 through a conduit 75 having a valve 76, but a portion of this condensate may be returned, if desired, through a branch line 77 having a valve 78 and a pump 79 and returned to the upper portion of the fractionating tower 43 as reflux.

The tower 43 is preferably provided at an intermediate point with a trap-out tray 81 so located as to make possible the withdrawal of a side stream consisting of a heavy gasoline fraction suitable for reforming purposes. This side stream is withdrawn from the trap-out tray 81 through a conduit 82 having a valved branch conduit 83 leading to a lower point in the tower 43 and a branch conduit 84 having a valve 85 and a pump 86.

Gases withdrawn from the separator 74 may be delivered to a fuel gas main or elsewhere through a pipe 88 having a valve 90, or may be diverted through a branch conduit 91 having a valve 92 and a gas pump 93.

From the foregoing it will be apparent that I have provided a combined stripping and cracking system which may variously be operated to produce virgin gas, gasoline and residual oil or reduced crude, as well as cracked gases, cracked gasoline, and pressure tar or residual oil resulting from the cracking operation, and also if desired a relatively heavy gasoline fraction of such character as to be well adapted to be subjected to a reforming operation.

As stated hereinabove, my invention contemplates the selective treatment of a desired number of such products, together with the ultimate combination of such stocks or the products resulting from the treatment of such stocks, under conditions favorable for polymerization and reaction to produce valuable low-boiling petroleum oils. While it will be apparent that I may variously accomplish the selective treatment of the stocks, in the present instance I have illustrated a preferred system which includes a furnace 100 provided with separate radiant heating coils 101 and 102 and convection heating coil 103, the products from which are delivered to a common reaction chamber 105, through transfer lines 106, 107 and 108, respectively.

In the instance illustrated in the drawing the radiant heating coil 101 is employed for the purpose of effecting the reformation or conversion of constituents of gasoline or naphtha to constituents of increased anti-knock value. Virgin gasoline from the separator 24 may be delivered to the coil 101 through a conduit 110 having a valve 111 and a pump 112, a conduit 113, and a conduit 114 having a valve 115. The heavy gasoline fraction withdrawn as a side stream from the trap-out tray 81 in the fractionating tower 43 may also be delivered to the coil 101 through a conduit 84 by means of the pump 86, and the conduits 113 and 114. Naphtha or gasoline from an outside source may also be delivered to the coil 101 by means of a conduit 116, wherein is located a pump 117 and a valve 118. Any of the aforesaid gasolines or naphthas may be employed alone or in any desired combination.

While in transit through the coil 101, the naphtha or gasoline is heated to a temperature of for example, from 850° F. to 1000° F. or even higher, under a suitable elevated pressure of, for example, from 200 to 750 pounds per square inch. Higher pressures of the order of 1000-1200 pounds may be used with advantage. The

hot reformed products then pass through the transfer line 106 to the reaction vessel 105.

At the same time relatively heavy hydrocarbon oil, preferably of residual character and preferably containing unsaturated hydrocarbon or other reactive constituents, is delivered to the reaction vessel 105. Pressure tar withdrawn from the bottom of the still 42 may be delivered directly to the reaction vessel 105 through the conduit 58 and a branch conduit 120 having a valve 121. Reduced crude withdrawn from the separating compartment 11 of the fractionation tower 4 may be forced by the pump 39 through the conduit 38 and through a line 122 having valves 123 and 124 to the convection heating coil 103.

While in transit through the coil 103 the oil is preferably heated to a mild cracking temperature of for example 800 to 850° F. under a pressure sufficient to permit the flow of the products through the transfer line 108 to the reaction vessel 105. By means of a conduit 126 having a valve 127 and a pump 128, heavy hydrocarbon oil of suitable character for treatment in the coil 103 may be introduced through the conduit 122 to the coil 103. Residual oil withdrawn from the still 42 may also be delivered by means of the pump 59 to the conduit 58, a conduit 130 having a valve 131 and a conduit 122 to the coil 103. The aforesaid stocks may be used either separately or in any desired combination.

If desired, gasoline or naphtha from the separator 24 or the trap-out tray 81 or both may be withdrawn from the conduit 113 through a branch conduit 132 having a valve 133 and communicating with the conduit 122, for the purpose of commingling with and diluting the heavy hydrocarbon oil introduced into the coil 103 and for the further purpose of making it possible to carry somewhat higher temperatures in the coil 103 than would otherwise be possible.

The oil while in transit through the coil 103 is, as aforesaid, heated to a mild cracking temperature to reduce the viscosity of the oil and to effect a mild cracking with the result that the content of unsaturated hydrocarbon or other reactive constituents in the oil may be increased and the products from the coil 103 are rendered more suitable for reaction and combination with other constituents under the conditions which obtain in the reaction vessel 105.

The coil 102 is preferably employed for the purpose of effecting a preliminary pyrolysis of gaseous hydrocarbons to promote the formation of gaseous unsaturated hydrocarbons, such as gaseous olefins, which are then delivered to the reaction vessel 105 through the transfer line 107. Thus gas liberated in the separator 24 may be withdrawn through a conduit 140 having a valve 141 and a gas pump 142, by means of which the gas is forced through the coil 102. Communicating with the conduit 140, I provide a gas conduit 143 having a valve 144 which may receive hydrocarbon gas from an outside source through a conduit 145, wherein is located a gas pump 146. By means of the conduits 145, 143 and 140 any hydrocarbon gas suitable for pyrolysis to effect formation of unsaturated hydrocarbon constituents may be introduced into the coil 102. Thus I may employ natural gas or other gas containing such constituents as ethane, propane, butane, pentane, ethylene, propylene and the like. While in transit through the coil 102, such gases are heated to a high cracking temperature of, for example, from 1100° to 1700° F.,

under a suitably elevated pressure of, for example, from 200 to 750 pounds per square inch or even higher, and the resultant pyrolyzed gases are then delivered through the transfer line 107 5 to the reaction vessel 105.

Where the hydrocarbon gases to be delivered to the reaction vessel 105 already contain sufficient quantities of gaseous olefins or the like, they may be delivered directly to the reaction vessel 105 without preliminary pyrolysis in the coil 102. Thus, cracked hydrocarbon gases from the gas separator 74 may be withdrawn through the conduit 91 and delivered by means of the gas pump 93 directly to the reaction vessel 105.

Furthermore, gases introduced into the system by means of the gas pump 146 may pass through the conduit 145 and a branch conduit 151 having a valve 152 directly into the reaction vessel 105.

While various types of reaction vessels may be employed, the reaction vessel 105 illustrated in the drawing represents the preferred type. This vessel comprises a more or less elongated vertical shell having an interiorly disposed annular baffle 155 which separates the interior of the vessel 105 into an annular compartment 156 and an inner compartment 157, which compartments 156 and 157 intercommunicate in the upper portion of the vessel 105. The various hydrocarbons to be reacted together in the vessel 105 are preferably introduced into the lower portion of the outer compartment 156 and pass upwardly through the latter before passing downwardly through the inner compartment 157. The products are then withdrawn through a conduit 158 30 having a valve 159 for delivery to an evaporator section 161 located within a fractionating tower 162. Conduits 158' having valves 159' and communicating with the conduit 158 may also be provided for the purpose of limiting or preventing accumulation of liquid products in the lower portion of the outer compartment 156.

The reaction vessel 105 is preferably maintained at a temperature effective to promote polymerization of normally gaseous hydrocarbons 45 to normally liquid hydrocarbons and interaction between the various unsaturated hydrocarbon or other reactive constituents which may be present, for example, at a temperature of 750 to 900° F. and under a pressure of from 200 to 750 50 pounds per square inch or even higher, for example from 1000 to 2000 pounds per square inch. As polymerization is favored by high pressure, it is, of course, desirable to maintain as high a pressure in the reaction vessel 105 as possible and in 55 practice this pressure is limited only by the pressures which it is possible to maintain in the coils 101, 102 and 103 from which the various products are delivered to the reaction vessel 105.

The products leaving the reaction vessel 105, in 60 passing through the conduit 158 to the evaporator section 161 are preferably considerably reduced in pressure by means of the valve 159 for example, to a pressure of from 50 to 200 pounds per square inch, and upon reaching the relatively low-pressure evaporator section 161, a separation of liquid and vapors occurs, the liquid being withdrawn from the bottom of the evaporator section 161 through a conduit 163 having a valve 164 while the vapors pass upward around a plurality of baffles 165 and through a trap-out tray 166 into the upper portion of the fractionating tower 162 which is provided as shown with a plurality of plates or trays 167.

By means of cooled reflux oil introduced into 75 the upper portion of the fractionating tower

162 through a conduit 168 or by means of cooling effected in any other suitable manner, the vapors passing upward through the fractionating tower 162 are subjected to a fractional condensation to such an extent as to make possible the 5 separation therefrom in liquid form of normally liquid products heavier than gasoline, that is to say, an intermediate or gas oil fraction, which is withdrawn from the trap-out tray 166 through a conduit 170 having a valved branch conduit 171 and a valved branch conduit 172 wherein is located a pump 173.

This gas oil may be removed from the system through the conduit 171 or, under the influence of the pump 173, may be recycled, either through 15 a line 174 having valves 175 and 176 to the conduit 45 and thence into the coils 46, 47, and 48, or through a line 177 having valves 178 and 179 to the conduit 122 and thence into the coil 103. In the latter instance, the gas oil is employed 20 as a diluent for the relatively heavy oil passing through the coil 103.

The gases and vapors remaining uncondensed at the top of the fractionating tower 162 are passed through a vapor line 180 to a condenser 25 181 and through a condensate line 182 to a gas separator 183. The condensate, consisting of naphtha or gasoline, is withdrawn from the separator 183 through a conduit 184 having a valve 185. A portion of this condensate may, however, 30 be diverted from the conduit 184 through the reflux line 168, wherein is located a valve 186 and a reflux pump 187, to be delivered to the top of the fractionating tower 162.

The gases passing out of the separate 35 183 may be removed from the system through a conduit 190 having a valve 191, or may be diverted in part through a branch line 192, having a valve 193 and a gas pump 194 to the conduit 140 to be recycled through the coil 102 for further pyrolysis.

It will be apparent to those skilled in the art that, while I have described hereinabove various preferred methods whereby a petroleum oil may be distilled, with the selective treatment of the 45 various products, and whereby petroleum products resulting from cracking of gases, reforming of naphtha and the cracking of heavy oil may be digested together under conditions favorable for the promotion of inter-reactions between reactive constituents of such materials, my process is not limited to such exemplification, but may be varied in accordance with the character of the materials treated and the nature of the results desired, within the scope of the claims 55 hereinafter made.

I claim:

1. The process of treating a petroleum oil which comprises introducing said oil into a distillation zone receiving hot cracked vapors, separately withdrawing residual oil and vapors from said zone, fractionating said vapors to separately recover therefrom normally gaseous hydrocarbons, a light gasoline fraction, a heavy gasoline fraction and a heavier gas-oil fraction, 60 independently subjecting said gas-oil fraction to a cracking temperature while in transit through a heating zone and discharging the resultant hot products into said distillation zone to supply said hot cracked vapors, subjecting said heavy gasoline fraction to conditions of temperature and pressure in a separate heating zone effective to promote reformation of constituents of said heavy gasoline fraction to constituents of increased anti-knock value, reacting the hot re- 65 70 75

formed products and normally gaseous hydrocarbons obtained as aforesaid with said residual oil under conditions effective to promote polymerization of gaseous hydrocarbons to normally liquid hydrocarbons, removing resultant products of said last-mentioned reaction and separately fractionating them to recover said normally liquid hydrocarbons.

2. The process of treating a petroleum oil which comprises introducing said oil into a distillation zone receiving hot cracked vapors, separately withdrawing residual oil and vapors from said zone, fractionating said vapors to separately recover therefrom normally gaseous hydrocarbons, a light gasoline fraction, a heavy gasoline fraction and a heavier gas-oil fraction, independently subjecting said gas-oil fraction to a cracking temperature while in transit through a heating zone and discharging the resultant hot products into said distillation zone to supply hot cracked vapors, combining said residual oil, normally gaseous hydrocarbons obtained as aforesaid and said heavy gasoline fraction under conditions of temperature and pressure effective to promote polymerization of gaseous hydrocarbons to normally liquid hydrocarbons, removing resultant products and separately fractionating them to recover a gasoline fraction therefrom.

3. The process of treating petroleum oil which comprises introducing said oil into a distillation zone receiving hot cracked vapors, separately withdrawing residual oil from said zone, fractionating vapors obtained from said zone to separately recover therefrom normally gaseous hydrocarbons, a gasoline fraction and a gas-oil fraction, independently subjecting said gas-oil fraction to a cracking temperature while in transit through a heating zone and discharging the resultant hot products into said distillation

zone to supply said hot cracked vapors, subjecting at least a part of said gasoline fraction to conditions of temperature and pressure in a separate heating zone effective to promote reformation of constituents of said gasoline fraction to constituents of increased anti-knock value, reacting the hot reformed products and normally gaseous hydrocarbons obtained as aforesaid with said residual oil under conditions effective to promote polymerization of gaseous hydrocarbons to normally liquid hydrocarbons, removing resultant products from said last-mentioned reaction and separately fractionating them to recover said normally liquid hydrocarbons.

4. The process of treating a petroleum oil which comprises introducing said oil into a distillation zone receiving hot cracked vapors, separately withdrawing residual oil and vapors from said zone, fractionating said vapors to separately recover therefrom normal gaseous hydrocarbons, a gasoline fraction and a heavier gas-oil fraction, independently subjecting said gas-oil fraction to a cracking temperature while in transit through a heating zone and discharging the resultant hot products into said distillation zone to supply said hot cracked vapors, combining said residual oil, normally gaseous hydrocarbons obtained as aforesaid and at least a part of said gasoline fraction under conditions of temperature and pressure effective to promote polymerization of gaseous hydrocarbons to normally liquid hydrocarbons, removing resultant products and separately fractionating them to recover a gasoline fraction therefrom.

5. A process in accordance with claim 4 wherein said residual oil is subjected to mild cracking prior to combining with said normally gaseous hydrocarbons and said gasoline fraction.

WILLIAM F. MOORE. 40
